UNITED STATES PATENT OFFICE.

SAMUEL I. FIELDS, OF CHEROKEE NATION, INDIAN TERRITORY.

CAR-COUPING.

SPECIFICATION forming part of Letters Patent No. 391,525, dated October 23, 1888.

Application filed March 17, 1888. Serial No. 267,508. (No model.)

To all whom it may concern:

Be it known that I, SAMUEL I. FIELDS, of Cherokee Nation, Indian Territory, have invented a new and Improved Car-Coupling, of 5 which the following is a full, clear, and exact description.

My invention relates to an improved car-coupling capable of attachment to the ordinary link draw-head without altering the same, and 10 has for its object to provide a cheap, simple, and effective coupling, whereby the cars may be automatically coupled and uncoupled without requiring train-men to pass between the draw-heads of opposing cars.

15 The invention consists in the construction and combination of the several parts, as will be hereinafter fully set forth, and pointed out in the claims.

Reference is to be had to the accompanying 20 drawings, forming a part of this specification, in which similar letters of reference indicate corresponding parts in all the figures.

Figure 1 is a plan view of opposing couplers in a coupled position. Fig. 2 is a central longitudinal section of the same, taken on the line 25 xx in Fig. 1; and Fig. 3 is a partial longitudinal section of opposing couplers in an uncoupled position.

30 A represents the draw-head, provided with a longitudinal groove, a' , at one side of its center adapted to receive a locking-bar, B. The locking-bar is pivoted or hinged at its inner end so as to have a slight vertical motion, and at its outer end, which projects beyond the draw-head, is provided with an essentially arrow-head-shaped hook, b, the member constituting the hook being upon its upper side. The upward movement of the locking-bar is limited by a staple or equivalent device, b', 35 spanning the same and secured to the draw-head. The groove a is widened from a point near its center outward and provided with an extension, a' , extending transversely of the draw-head beyond its center, as shown in Fig. 1.

40 An angle-lever, D, is pivoted to the side of the locking-bar, its horizontal member resting normally in the enlargement of the groove a parallel with the locking-bar and terminating, preferably, at the face of the draw-head, and 45 said horizontal member is provided with an arm, d , at right angles thereto, seated normally in the transverse extension a' of the groove a .

The vertical member of the lever may extend upward a distance beyond the car-sill and be operated therefrom or be carried to the roof of 55 the car, or united by a chain connection with a second lever pivoted upon the roof, whereby the angle-lever may be manipulated either from the sill or roof, as desired. The movement of the angle-lever is controlled by a pin, 60 d' , integral with the locking-bar, engaging the walls of a recess, d^2 , in the horizontal member of the angle-lever when said member is elevated.

A loop-link, E, is pivoted or hinged upon 65 the upper face of the draw-head and projects beyond the front face of the same, the link being normally held in a horizontal position by a spring, E', having a right-angled arm or extension, e' , which bears on said link. In the 70 edge of the draw-head, within the space surrounded by the link, a beveled recess, e , is provided, adapted to freely receive the under side of the hook-head of the opposing locking-bar when the cars are coupled or in process of 75 coupling.

It will be observed that the coupling herein described may without difficulty and little expense be attached to any link-and-pin draw-head without interfering with their operation 80 as such. It will be also observed that by means of the groove a the locking-bar is protected against lateral strain.

In operation as the opposing draw-heads approach each other the link of one draw-head 85 will pass over the head of the locking-bar of the opposing draw-head and engage it, as shown in Fig. 1. To uncouple, the vertical member of either lever D is depressed, whereupon one link will be disengaged by the outer end of the 90 horizontal member and the other link simultaneously by the arm d , as partially shown in Fig. 3.

Having thus described my invention, what I 95 claim as new, and desire to secure by Letters Patent, is—

1. The combination, with the draw-head, of a longitudinal pivoted locking-bar provided with an outer hooked extremity, an angle-lever pivoted to said locking-bar, and a spring-actuated link pivoted to the draw-head at one side 100 of and parallel with the locking-bar, substantially as shown and described.

2. The combination, with the draw-head pro-

vided with a longitudinal groove and a beveled front recess, of a locking-bar pivoted in said groove, provided with an outer hooked extremity, an angle-lever pivoted to said locking-bar, and a spring-actuated link pivoted upon the draw-head and extending over the recess therein, substantially as herein shown and described.

3. The combination, with the draw-head provided with a longitudinal groove, a transverse groove intersecting the same, and a beveled front recess, of a locking-bar pivoted in said groove, provided with an outer hook-shaped

extremity, an angle-lever pivoted to the locking-bar, located in said longitudinal groove 15 and provided with a transverse arm resting in the transverse groove, a spring-actuated link pivoted upon the draw-head, extending over the recess therein, and the lever-arm, all combined to operate as and for the purposes specified.

SAMUEL I. FIELDS.
